UNITED STATES PATENT OFFICE.

WILLIAM E. WINN, OF PITTSBURGH, PENNSYLVANIA.

PNEUMATIC SYSTEM FOR CLEANING COAL OR ORE.

1,295,248.

Specification of Letters Patent. Patented Feb. 25, 1919.

Application filed March 3, 1917. Serial No. 152,251.

To all whom it may concern:

Be it known that I, WILLIAM E. WINN, a resident of Pittsburgh, in the county of Allegheny and State of Pennsylvania, have 5 invented a new and useful Improvement in Pneumatic Systems for Cleaning Coal or Ore, of which the following is a specification.

This invention relates to a method and 10 apparatus for cleaning coal, ore, etc.

Among the objects of the invention are the removal of slate, etc., which may be classed as impurities. Another object is to do this by a dry method, saving all the dust, 15 mother coal, and lighter matter, which is in large measure lost in the case of washing the coal in water or density solutions to separate the impurities. Another object is to furnish means and use a method by which 20 the coal is moved past the separating means.

While a method of cleaning coal is particularly described, it will be understood that certain other mixtures, such as ore and gangue might be similarly treated. Also, 25 matter containing heat values may be separated from the waste matter in ashes of cleaning pits at locomotive yards, etc.

These objects are attained by air exhaust and suitable conveying and handling devices. The separation is done by subjecting the mixture in a sized condition, to the action of an air exhaust. It is a well known fact that when particles of matter of substantially the same size but of different specific gravities, are subjected to a flow of fluid, the direction of which is opposed to gravity, those particles of relatively smallest specific gravity will be most affected by the fluid current, and consequently moved to a 40 greater distance thereby. In the present case an air exhaust is applied to sized coal, etc., tending to raise it vertically, against the force of gravity. This raises the lighter particles of coal, while the heavier impurities 45 are not raised. Thus, in effect, the present invention draws off the coal, and leaves impurities, such as slate, pyrites, rock, fire clay, bone coal, etc., thus effecting a mechanical separation, without the use of water, 50 and one that has many advantages, as will appear more fully throughout the following specification.

Referring to the drawings, Figure 1 shows a vertical cross section through the apparatus on the line 1—1 of Fig. 2; Fig. 2 55 shows a vertical longitudinal partial sec-

tion; Fig. 3 shows a vertical cross section on line 3—3 of Fig. 2; Fig. 4 is a vertical cross section on the line 4—4 of Fig. 2; Fig. 5 is a vertical section showing details of a 60 valve, and Fig. 6 is a detail view on an enlarged scale of adjusting means for the suction boxes.

The apparatus is housed in a suitable building comprising a foundation floor 1, 65 walls 2, structural supporting beams 3, etc. Running lengthwise of the building are a series of parallel endless conveyers A and a central endless conveyer B. Conveyers A are carried on supports 5 and comprise 70 linked pans 6 carried on rollers 7, said pans constituting an endless conveyer, returning underneath by means of rollers 7^a, as will be readily understood. In the drawing four of these conveyers are shown, but it will be 75 understood that this number may be varied to suit any particular set of circumstances. At the left of Fig. 2 are transverse conveyers C and D, later described.

Situated above the pans 6 (Fig. 1), at 80 some point over each of the conveyers, are inverted funnel-shaped boxes 8, extending across the pan conveyers, fitting closely and having only slight clearance from the upturned edges 6^a of said pans. These boxes 85 are supported by cogged shafts 9, across the supports 5, said shafts having terminal hand wheels 10. The shafts are so connected to pipes 11, which extend to the boxes 8 by a rack 9^a, that by rotation of the hand 90 wheels 10, the pipes and suction boxes may be raised and lowered, to adjust the relation of the boxes and pan conveyers, for reasons which will appear more clearly hereinafter. In order that the pipes 11 may be readily 95 raised and lowered, flexible joints 12 are placed therein, consisting of rubber or fabric, which readily allows adjustment in the length of said pipes. The details of this raising and lowering means are more clearly 100 shown in Fig. 6. Gates 13 are arranged to open and close these pipes, and these are controlled by cords 14, running over pulleys 15 carried by rigid supporting members 16. These cords have terminal hand rings 17 at 105 a point conveniently within the reach of an operator standing beside the conveyer, so that a pipe 12 is readily opened or closed from that point.

Pipes 11 lead into air-tight tanks 18, 110 which have conical hopper bottoms 19, ending in outlet pipes 20, which are controlled

by rotary valves 21 (Fig. 5) consisting of shafts 22 having four blades or gates 23 situated at right angles to each other, in cylindrical casings 24, upper and lower openings 25 and 26 in said casings being slightly less than 90 degrees of the circumference of the cylindrical chamber in which the valve works. By this means the rotation of shaft 22 will discharge solid matter from the bottom of the conical chamber; but at all times the openings will be sealed against escape of air therethrough. The shafts 22 are driven by suitable belt connections to a motor M, as shown in Fig. 2. The compartment 18 is supplied with an air gage 27, and a man-hole 28, as illustrated.

From the top of this compartment a pipe 29 leads to an exhaust device 30, which may be of any of the well known forms, such as a fan, or pump. This exhaust device may be driven by means of a motor 31 suitably geared thereto. The pipe 29 has a continuation 32 beyond the exhaust device, leading into a chamber 33, the bottom of which 25 slants to troughs 34 in which are rotary screw conveyers 35, driven by suitable belt connections to a motor M, as shown in Fig. 4, adapted to carry dust collected in the troughs, as hereinafter described, to the end 30 of the conveyer; where it then falls into chutes 36, leading to an outlet pipe 37, emptying upon conveyer B, as later described.

In the illustration the compartment 18 has four of the connecting pipes 11, extending to the parallel conveyers A. It will be understood, however, that ordinarily only one of the pipes 11 will be opened at a time, so that the full force of the exhaust of a 40 vacuum chamber 18 will be applied at one point. The purpose of having the multiple connections is to give adjustability, and to permit the use of each exhaust unit with any one of the parallel conveyers without 45 shifting of mechanism.

This apparatus is intended to handle particles of small size, and ordinarily the coal to be cleaned will be put through a crushing plant, which is not here shown, and which 50 may be any of the well known constructions, from which plant it is delivered onto an endless belt conveyer E, driven by a motor M', as shown in Fig. 2. It is preferred to reduce the coal to particles varying from $\frac{1}{2}$ 55 inch in diameter to dust, and then to screen this into four sizes; $\frac{1}{2}$ inch to $\frac{3}{8}$ inch cubes, $\frac{3}{8}$ inch to $\frac{1}{4}$ inch cubes, $\frac{1}{4}$ inch to $\frac{1}{8}$ inch cubes, and $\frac{1}{8}$ inch cubes to dust, respectively. But this will depend upon and vary with the 60 character of the coal and of the impurities found in it. This belt discharges into a bin 38 having a conical hopper bottom 39, with an outlet 40, leading to a trough 41, in which rotary screw conveyers 42 operate to carry 65 material to chutes 43, leading to rotary

screening drums 44. These are preferably in the form of the frustum of a cone, the coal being fed into the smaller end, and they comprise a perforated sheet metal wall, or other screening medium, divided into 70 three or more zones, in each of which the meshes are of a different size. These screening drums are mounted on central shafts 45, which rest upon suitable supports, and which are driven by a belt connection to a 75 power shaft driven by motor M, as shown in Fig. 3.

Just underneath this drum is situated a receiving hopper which is divided into sections 46, 47, 48, each adapted to receive the 80 sized material passing from one of the zones of the screening drum. Consequently the material passing the drum in the first zone falls into the first division of the receiving hopper, and is carried off by a chute 49. 85 Similar chutes lead from the other divisions of the receiving hopper below zones 47 and 48 of the drum, and from the end of the drum, and these chutes lead respectively to receiving tanks, or reservoirs 50.

These hoppers, as shown in Fig. 3, have conical shaped bottoms 51, controlled by gates 52, from which lead chutes 53 to terminal receiving boxes 54, which are adapted to receive and store the granulated coal, and to 95 distribute it therefrom to the endless conveyers A comprising endless pans or moving tables 6, which are mounted on upper rollers 7, and which return underneath by means of lower rollers 8, as above described. 100 These tables are driven by any suitable means, as for example, motor M, and suitable connections to a driving wheel 55, as shown in Fig. 2.

After passing under the induction nozzle 8, above described, these conveyers A extend to chutes 56, into which is discharged any matter remaining thereon; these chutes leading to a transversely arranged endless conveyer D, which in turn extends to a discharge point, where the material is dumped into a car or other suitable receptacle.

Another conveyer B, consisting of an endless belt carried on rollers b above and b' below extends beneath the chutes 20, above described, and terminates by discharging into a chute 56, which carries the clean coal to an endless conveyer C similar to the conveyer D, which terminates at any desired point where the clean coal is to be stored or loaded. The construction and mounting of conveyers C and D are similar to that of the conveyer B.

It will be understood that the various conveyers referred to are driven by suitable connections to the motor M, or to any other source of power, such means being well understood and not peculiar to this invention. Workable connections are illustrated in the various views.

The operation of my apparatus is as fol-

lows:—Coal is crushed at any suitable point, and is delivered by the conveyer E to the hopper 38, from which it passes by the chute 43 to the screening drums 44, by which it is 5 separated into four sizes, which are respectively delivered by means of chutes 49, to the storage bins 50. These reservoirs are situated over the conveyers A, and by means of the gates 52 and spreading delivery boxes 54, the crushed coal is spread evenly upon the moving tables 6, and by them is conveyed 10 underneath the suction hoods 8.

By means of the exhaust device 30 a partial vacuum is maintained in the tanks 18, 15 so that there is a constant upward rush of air in the induction pipes 11. The hoods 8 are raised and lowered by the operator by means of hand wheels 10, to regulate the suction sufficiently to raise the lighter particles 20 of coal from the movable tables, and carry them upwardly through the pipe 11 and into the chamber 18, where they immediately fall to the bottom, and are discharged by means of the rotating gate valve 21, onto the conveyer B, and thereby carried to the conveyer 25 C which extends to a car or other suitable storage point.

The heavier impurities, such as slate, and rock, are not raised by the air exhaust, and 30 remain upon the movable tables, being carried to the end thereof, and dumped through the chute 57 onto the conveyer D, and thence carried to any desired point.

A certain amount of dust and fine "mother coal" will be drawn through the exhaust 35 device 30, and will pass into chamber 33, and thence after settling by chutes 36 to the conveyer B, with the cleaned coal.

Copies of this patent may be obtained for five cents each, by addressing the "Commissioner of Patents, Washington, D. C."

I claim:—

1. The method of separating impurities 40 from coal comprising the steps of crushing the coal to separate the particles of coal from particles of impurities, screening the mixture to uniform size and then subjecting the mixture on a continuous conveyer to a 45 vertically applied air exhaust.

2. The method of separating impurities from coal comprising the steps of separating the mixture into different sizes, exposing the several sizes of mixtures separately in a thin 50 layer on a flat surface to a vertically applied air exhaust to draw off the lighter particles, and separately discharging the different materials.

3. The method of separating coal from 55 other matter of different specific gravity from coal, comprising the crushing and sizing of the mixture, the spreading of the mixture in a uniform layer on a flat surface, and the passing of the flat surface under an 60 upward air exhaust, whereby the lighter matter is drawn off from the mixture.

4. Apparatus for cleaning crushed coal, comprising means to grade the mixture into particles of uniform size, continuous conveyers adapted to hold the mixture in a thin 65 layer, an exhaust device adapted to apply a vertical air draft to the layer of crushed material whereby to draw off the lighter particles, and means to discharge the separated materials from the apparatus. 70

In testimony whereof I have hereunto set my hand.

WILLIAM E. WINN.
